UNITED STATES PATENT OFFICE.

PAUL HENRY WALLER, OF CAMBERWELL, LONDON, ENGLAND.

SIGNALING OR INDICATING APPARATUS.

1,390,001.

Specification of Letters Patent.

Patented Sept. 6, 1921.

Application filed December 10, 1919. Serial No. 843,968.

To all whom it may concern:

Be it known that I, PAUL HENRY WALLER, a citizen of the Republic of France, residing at Camberwell, in the county of London, S.

5 E., England, whose post-office address is 41 Wilson road, Camberwell, in the county of London, S. E., England, have invented certain new and useful Improvements in or Relating to Signaling or Indicating Apparatus; and I do hereby declare the following to be a full, clear, and exact description of the invention, such as will enable others skilled in the art to which it appertains to make and use the same.

10 15 This invention is for improvements in or relating to signaling or indicating apparatus such as station indicators, and has for one of its objects to provide a construction of mechanism which can be cheaply installed 20 and which will be efficient in its working.

According to one feature of the present invention there is provided in signaling or indicating apparatus (for example a station indicator) of the type comprising an 25 electrical driving mechanism for the signaling or indicating device and a circuit closer for such driving mechanism operated by a member on a vehicle engaging with a ramp or other impact or contact device on the 30 track, the combination with the circuit closer of an electrically released lock to hold it closed and a switch operated by the driving mechanism at the end of a step in its operation to release the said lock. Thus it is insured that the operating circuit for the 35 driving mechanism will remain closed until the desired step in its operation has been imparted to the driving mechanism.

According to another feature of the invention there is provided a signaling or indicating apparatus (for example a station indicator) and a operating mechanism comprising in combination:—

(a) An electrical contact maker adapted 45 to be mechanically moved into position against mechanical withdrawal force to close the operating circuit of the step-by-step mechanism by the passage of a vehicle past a member on the track (for example a stop 50 which co-operates with a spring-balanced lever to operate the contact maker).

(b) An electrically released lock to maintain the contact maker in such circuit-closing position until the desired step in its operation has been imparted to the step-by-step mechanism, and

(c) Means automatically operated by the step-by-step mechanism at the completion of each step in its operation to operate the said electrical release and permit the mechanical withdrawal of the contact maker from circuit-closing position.

Other features of the invention relate to the provision of means for enabling the apparatus to operate for either direction of travel of the vehicle, and for permitting temporary reversals in the direction of travel to take place without destroying the correctness of the signals or other indications given by the apparatus.

For a more complete understanding of the invention there will now be described by way of example only and with reference to the accompanying drawings certain constructional forms of mechanism according to the present invention. It is to be understood, however, that the invention is not limited to the precise constructional details enumerated.

In the accompanying drawings:—

Figure 1 is a diagrammatic illustration of 80 certain parts of the mechanism according to the invention, together with certain electrical circuits therefor.

Fig. 2 is an illustration, on a scale larger than that of Fig. 1, of certain parts of the 85 mechanism some only of which parts are illustrated in Fig. 1.

Fig. 3 is a view, on a scale larger than that of Fig. 1, illustrating a modification of the apparatus which will operate for either di- 90 rection of travel of the vehicle.

Fig. 4 is an end elevation of the parts shown in Fig. 3 looking in the direction of the arrow 44 in Fig. 3.

Fig. 5 is a plan view corresponding somewhat to Fig. 2 but showing the apparatus modified to permit temporary reversals in the direction of travel to occur without destroying the correctness of the signals or other indications given by the apparatus.

Fig. 6 is an end view of the parts shown in Fig. 1 showing them in one of the positions which they occupy, and

Fig. 7 is a view corresponding to Fig. 6 showing the parts in another position which they occupy.

Like reference numerals indicate like parts throughout the drawings.

The mechanism may be used in connection with various types of signaling and indicating apparatus but it may also be used in connection with other similar apparatus.

Referring to Figs. 1 and 2, an operating shaft of a step-by-step mechanism for driving the apparatus is indicated at 1 and this is provided with a toothed driving wheel 2 which may, if desired, be prevented from return movement by a pawl, not illustrated. It will be understood that any convenient type of signaling or indicating apparatus can be operatively attached to the shaft 1 to be driven thereby.

The shaft 1 is intended to receive a partial rotation whenever a vehicle passes a station. For this purpose the track over which the vehicle runs is provided with a stationary stop 3 so placed as to be struck by one end of a lever 4 carried by the vehicle. In Fig. 2 the arrow 5 illustrates the direction of travel of the vehicle. The lever 4 is pivoted at 6 and is slotted at 7 to receive a pin 8 on a bar 9. This bar 9 is mounted to slide in suitable guides 10, 11 and is provided with collars 12, 13 and springs 14, 15 appropriated respectively to the collars 12 and 13. The springs 14 and 15 each bear at one end against a collar and at the other end against a stationary abutment such as the guides 10, 11 and by this means the bar 9 and consequently the lever 4 are resiliently pressed toward a median position. It will be appreciated, however, that longitudinal movement of the bar 9 and consequential rotational movement of the lever 4 will be permitted, one or other of the springs 14, 15 being compressed during such movement.

The end of the lever 4 which is remote from the stop 3 is adapted to engage the end of a bar 16 which serves as a contact maker and circuit closer for the operating circuit of the step by step mechanism as will now be described. The bar 16 is mounted to slide in guides 17 and is provided with a collar 18 between which and one of the guides 17 is mounted a spring 19 which tends to withdraw the bar 16 from circuit-closing position. The contact with which the end of the bar 16 engages to complete the circuit is indicated at 20 in Fig. 1, and to retain the bar 16 in its circuit-closing position it is slotted at 21 to receive the end 22 of a pivoted catch 23 to which is attached a rod 24 pressed by a spring 25 in the direction to tend to force the end 22 of the catch 23 into the slot 21 in the bar 16. A portion of the rod 24 constitutes the core of an electromagnet 26 which when energized moves the rod 24 against the pressure of the spring 25 in the direction to release the catch 23 from engagement with the bar 16.

The operating circuit for the step by step mechanism comprises a battery or other source of current 27 whereof one lead 28 is connected to the bar 16 and the other lead 29 is connected to the coil 30 of an electromagnet for operating the step by step

mechanism, and proceeds thence to the contact piece 20. Thus it will be seen that when the bar 16 makes contact with the contact piece 20 the circuit will be closed and the electromagnet included in it, namely the coil 30 energized. The coil 30 surrounds a core 31 formed of a portion of a bar moving in guides 32 and pressed downward by a spring 33 working in conjunction with a collar 34 on the core 31. Connected to the end of the core 31 is a pivoted pawl 35 having a tooth 36 which engages the teeth on the wheel 2. When the coil 30 is energized it draws the core 31 upward against the pressure of the spring 33 and thus moves the wheel 2 through one step, corresponding to the pitch of its teeth. Then when the operating circuit is broken the spring 33 returns the core to its lower position and resets the pawl 35 in position to engage another tooth on the wheel 2.

As described above, when the bar 16 moves into circuit-closing position, the catch 23 engages the slot 21 in the bar 16 and locks the latter in circuit-closing position. It is intended that this lock should be released as soon as the desired partial rotation has been imparted to the wheel 2. To effect this release automatically, a sliding contact 37 is provided which co-operates with another contact 38. The sliding contact 37 moves in guides 39 and is normally pressed downward by a spring 40 co-operating with a collar 41 on the contact 37. As the core 31 approaches the upward limit of its travel it engages the sliding contact 37 and pushes it against the contact 38. The contact 37 is connected to a lead 42 of a source of current, say the battery 27 and the contact 38 is connected to another lead 43 from that source of current. The lead 43 includes the coil 26 of the electromagnet controlling the catch 23, thus when the core 31 reaches the upward limit of its travel it will close the contact 37 upon the contact 38 and energize the coil 26 to withdraw the catch 23 and permit the spring 19 to move the bar 16 out of the position in which it closes the operating circuit of the step by step mechanism. From the foregoing it will be seen that the operating circuit for the step by step mechanism will remain closed until the desired step in rotation has been imparted to the wheel 2, when the circuit will be automatically broken by the electrical withdrawal of the locking catch 23.

In operation, as the vehicle carrying the lever 4 passes the stop 3 in the direction of the arrow 5 the latter will move the contact maker 16 into operative position, in which position it will be retained by the catch 23. The lever 4, however, will under the influence of the springs 14, 15 return to mid-position. The operation of the step by step mechanism and the automatic return of the

contact maker 16 to inoperative position have already been described in detail and need not be further explained. By having the lever 4 separate from the contact maker 5 16 it will be seen that movement of the vehicle in the direction opposite to that of the arrow 5 will not cause operation of the step-by-step mechanism.

The apparatus has been described above 10 as being carried upon the vehicle but it will be appreciated that this is not essential since the apparatus could be placed adjacent the track and the vehicle carry a member, say something similar to the part 3 above described, to coöperate therewith.

The apparatus described above is only operative for one direction of travel of the vehicle. To enable it to be operative for both directions of travel, the shaft 1 may, as 20 shown in Figs. 3 and 4, be provided with two oppositely-toothed driving wheels 2 and 45. Coöoperating with these wheels 2 and 45 are two sets of operating mechanism whereof only the pawls 35, 36 and 46, 47 and cores 25 31, 48 are shown. These sets of operating mechanism are similar to the mechanism already described in connection with Figs. 1 and 2 and are appropriated one to one direction of travel of the vehicle and the other 30 to the opposite direction of travel of the vehicle and are operative accordingly. They are intended to be placed with their contact makers one on each side of the lever 4, which latter will not be duplicated, and it will be seen that they are coupled to the shaft 1 in such manner that one set of mechanism will drive the shaft in one direction and the other set will drive it in the opposite direction. Thus when the vehicle is traveling in one 40 direction the shaft 1 will be rotated in one direction and when the vehicle is traveling in the opposite direction the shaft 1 will be rotated in the opposite direction.

Intermediate of the wheels 2 and 45 the 45 shaft 1 is shown provided with a toothed member 49 which participates in the movement of the shaft and with which there co-operates a restraining catch 50 on one end of a spring 51 which at its other end is 50 mounted upon a suitable bracket 52 upon some stationary portion of the apparatus. The catch 50 will coöperate with the toothed member 49 to prevent undesired rotation of the shaft 1 but it will be understood that the 55 catch 50 will be forced out of operative position when either of the pawls 35 and 46 positively rotate the shaft 1.

Instead of duplicating the operating mechanism as just described with reference to 60 Figs. 3 and 4, an arrangement similar to that shown in Figs. 5, 6 and 7 can be adopted. This arrangement of apparatus is intended to render the operating mechanism inoperative for one step in its operation consequent upon the backward movement of the

vehicle past the member on the track and to reset the operating mechanism in operative position or condition consequent upon the next ensuing passage forward of the vehicle past such member on the track. 70 In the construction illustrated this is effected by moving the contact maker 16 out of operative alinement with the lever 4 when the said backward movement of the vehicle takes place, and returning it into operative 75 alinement when the next ensuing forward movement of the vehicle takes place. For this purpose there is provided a slide 53 mounted to move in guides 54 and slotted or recessed at 55 to house the lever 4. The proportions 80 of the slot or recess 55 are such that when the parts are in the position illustrated in Figs. 5 and 6, the slide 53 will not be moved by displacement of the lever 4 consequent upon contact with the member 3 during 85 travel of the vehicle in the direction indicated by the arrow 5. The slide 53 is provided with an extension 56 the end of which reaches toward a cam 57 upon the bar 16. This bar 16 in the construction illustrated 90 in Figs. 5, 6 and 7 is supported in guides 17 in wide slots 58. These slots 58 permit the bar 16 to occupy two distinct positions, namely as illustrated in Figs. 6 and 7, in one of which, Fig. 6, the bar is in operative 95 alinement with the lever 4, and in the other, Fig. 7, the bar is out of operative alinement with the lever 4. The bar 16 is pressed into operative alinement with the lever 4 by springs 59 and is brought out of this position by engagement between the extension 56 and the cam 57, as illustrated in Fig. 7. Backward movement of the train will move the lever 4 in the direction opposite to that indicated by the arrow 5 and cause the extension 56 to slide upon the cam 57 and press the bar 16 into the position shown in 100 Fig. 7. Ensuing forward movement of the vehicle past the stop 3 will move the slide 53 to bring its extension 56 off the cam 57 and 110 to permit the springs 59 to return the bar 16 in alinement with the lever 4 so that at the next forward movement of the lever 4, consequent upon the passage of the vehicle past another stop 3, the bar 16 will be operated 115 by the lever 4. By this means the effect of the backward movement of the vehicle past the stop 3 is canceled and the correct working of the signaling or indicating apparatus is not interferred with. It will be appreciated that the slot 55 will permit normal working of the lever 4 to proceed without 120 operating the slide 53.

Obviously the apparatus illustrated in Figs. 3 and 4 and Figs. 5 to 7 may either be 125 carried upon the vehicle or be placed adjacent the track as found most desirable.

As has already been stated the invention is not limited to the precise mechanical and electrical details shown and described since 130

these may be modified in certain respects without departing from the spirit and scope of the invention.

What I claim as my invention and desire to secure by Letters Patent is:—

- 5 1. In a signal apparatus, the combination, with a pivoted lever adapted to be operated by contact with an obstacle, of a longitudinally slidable circuit closer operated in one direction by the said lever, a spring for moving the circuit closer in the reverse direction, a driving shaft, a ratchet toothed wheel and a pawl for revolving the said shaft step by step, a solenoid operatively connected with the said pawl, an electric circuit adapted to energize the solenoid and provided with a contact piece arranged in the path of the said circuit closer, and a locking device which holds the said circuit closer closed while the 10 ratchet wheel and pawl are being actuated by the solenoid.
- 15 2. In a signal apparatus, the combination, with a pivoted lever adapted to be operated by contact with an obstacle, of a longitudinally slidable circuit closer operated in one direction by the said lever, a spring for moving the circuit closer in the reverse direction, a driving shaft, a ratchet toothed wheel and a pawl for revolving the said shaft step by step, a solenoid operatively connected with the said pawl, an electric circuit adapted to energize the solenoid and provided with a contact piece arranged in the path of the 20 said circuit closer, a locking device adapted

to hold the circuit closed while the ratchet 35 wheel and pawl are being operated by the solenoid, an electro-magnet adapted to retract the said locking device, a switch which is closed by the said solenoid after it has operated the pawl and the ratchet wheel, 40 and an electric circuit having the said switch and electro-magnet included in it and adapted to energize the latter.

3. In a signal apparatus, the combination, with a pivoted lever adapted to be operated by contact with an obstacle, of a longitudinally slidable circuit closer operated in one direction by the said lever, a spring for moving the circuit closer in the reverse direction, a driving shaft, a ratchet toothed wheel and 50 a pawl for revolving the said shaft step by step, a solenoid operatively connected with the said pawl, an electric circuit adapted to energize the solenoid and provided with a contact piece arranged in the path of the 55 said circuit closer, a locking device which holds the said circuit closer closed while the ratchet toothed wheel and pawl are being actuated by the solenoid, and means operated by the said pivoted lever for moving the 60 said circuit closer laterally out of alignment with the said pivoted lever when the said lever is moved backwardly by contact with an obstacle and it is not desired to operate the said driving shaft.

In testimony whereof I have affixed my signature.

PAUL HENRY WALLER.
